UNITED STATES PATENT OFFICE.

MARSHALL R. DOWLIN, OF NORTH ADAMS, MASSACHUSETTS.

SURCINGLE.

SPECIFICATION forming part of Letters Patent No. 257,672, dated May 9, 1882.

Application filed December 12, 1881. (No model.)

To all whom it may concern:

Be it known that I, MARSHALL R. DOWLIN, of North Adams, Berkshire county, Massachusetts, have invented certain new and useful 5 Improvements in Surcingsles, of which the following is a specification.

The ordinary surcingle used to hold the blanket upon a horse, as is well known, is a more or less padded strap, similar to a small 10 harness-saddle, which bears upon the back of the horse, on the ridge of the backbone and on either side thereof, and is so held by a strap, which is buckled around the blanketed body of the horse. Owing to the flexible nature of 15 the pads of this surcingle it is liable to gradually work over the backbone from one side to the other, and thus become displaced by the various movements of the horse, particularly as he lies down or gets up, thereby allowing 20 the blanket to become displaced and frequently injured by his hoofs, at the same time leaving his body unprotected. Moreover, if the surcingle be strapped tight, with a view to prevent this displacement, the strain is exerted 25 chiefly on the ridge of the backbone, which renders the horse uneasy or irritated, and particularly is this the case with a sick horse or with one whose back is sore or galled from the saddle. I have therefore appreciated the need 30 of an improved surcingle which would be so formed as to apply its pressure upon the soft flesh on either side of the backbone without bearing appreciably, or at all, upon the ridge, so as to prevent the tendency to slip over the 35 ridge from one side to the other, or to irritate the backbone, as in the existing surcingsles. This I effect by forming a surcingle with two 40 stiff or inflexible pads or bearers joined by a flexible connection or hinge, and the whole provided with a strap or band to be buckled around the body of the horse in the usual manner.

My invention consists in the general construction of the various parts, as more fully 45 hereinafter described and claimed.

In the annexed drawings, Figure 1 presents an elevation of my improved surcingle viewed edgewise, or in such position as it would appear in cross-section, taken through the body 50 of a horse around which it was buckled. Fig. 2 is a plan view on a larger scale, the main

portion of the buckling strap or band being cut off. Fig. 3 is an inverted plan or inversion of Fig. 1. Fig. 4 is an end view in the same direction as Fig. 1, showing, however, only the 55 pads and their connector in section on a larger scale.

In the drawings, *a a* indicate two inflexible pads or bearers, which form the main portion of the surcingle, and which are joined together 60 at their approaching ends by a flexible hinge strap or connector, *b*. The pads in form accommodate the fleshy curves or hollows on either side of the backbone of the horse, as will be understood from Fig. 1. I prefer to make 65 these pads *a a* from solid blocks of light strong wood and to form the connector *b* of a strap of leather fastened at its ends to the pad-blocks *a a*. The pads and their connector are attached, 70 of course, to a buckling-strap, *d*, which is passed around the blanketed body of the horse and buckled on one side, as seen in Fig. 1, the pads bearing, as usual, on the top of the back to hold the blanket in place, as shown in Fig. 1, 75 but in an improved manner, as hereinafter described.

In case the strap *d* be made of leather it may be riveted directly to the connector *b* and also to the pads *a a*; but if it be made of woven webbing, as I prefer for cheap surcingsles, then 80 the web is attached simply by one or two rivets, *e e*, (see Figs. 1 and 2,) to the center of the connector *b*, and it passes through or under little leather loops *h h*, fastened to the blocks *a*, near their outer ends, as seen best in Figs. 1 85 and 2. One end of the web is provided with a projecting leather tongue, *f*, stitched thereto, while the other end is provided with a buckle, *g*, whereby the strap may be buckled upon the horse in the usual manner, as will be understood from Fig. 1. It will hence be seen that by connecting the web-strap, as described, with the pads of the surcingle, when the strap is buckled on the horse the tension on the strap 90 will be distributed lengthwise on its own texture, and will not be exerted on the rivets or fastening *e*, by which it is held to the connector *b*, thus rendering the connection strong and simple and obviating any tendency of the connection or strain to tear the web, as will be readily understood.

I am aware that harness-saddles have some-

times been made with wooden blocks; but my invention is obviously distinct from this.

What I claim is—

1. A surcingle formed with two distinct inflexible bearing-pads, separated so as to freely admit the ridge of the backbone between them, and adapted to bear on the fleshy parts of the back, on either side of the ridge, with a flexible connection between said pads, adapted to span the backbone without bearing seriously thereon, together with a buckling-strap for fastening the same around the blanketed body of the horse, substantially as herein shown and described.
- 15 2. A surcingle constructed with bearing-pads formed of wooden blocks joined by a flexible connection or hinge, substantially as and for the purpose set forth.

3. The combination, in a surcingle with inflexible bearing-pads and their connection, of 20 the buckling-strap *d*, fastened to the middle of the said connections and free in both directions therefrom, but passing loosely over the pads, substantially as and for the purpose set forth.

4. The combination, in a surcingle, with inflexible bearing-pads and their connector, of the buckling-strap *d*, fastened to the middle of the connector, with loops *h h* near the outer ends of the pads, through which the strap is 30 loosely passed, substantially as herein shown and described.

MARSHALL R. DOWLIN.
